UNITED STATES PATENT OFFICE.

JAMES A. TAYLOR, OF BIRMINGHAM, ALABAMA.

SIGNAL ATTACHMENT FOR LOCOMOTIVES.

Application filed August 12, 1927. Serial No. 212,565.

This invention relates to a single attachment for locomotives and is designed more particularly as an improvement upon the structure disclosed in Patent No. 1,558,945 5 issued to me on October 27, 1925.

One of the objects of the invention is to provide improved mechanism for controlling the flow of steam to the whistle of the locomotive, the mechanism being greatly simplified and 10 cheapened in construction and permitting the whistle to be operated at any distance desired from the engineer cab.

Another object is to provide improved means under the control of trips located 15 against the railway track, whereby a predetermined signal will be sounded by the whistle as the locomotive passes the trips.

With the foregoing and other objects in view which will appear as the description 20 proceeds, the invention resides in the combination and arrangement of parts and in the details of construction, hereinafter described and claimed, it being understood that changes 25 in the precise embodiment of the invention herein disclosed may be made within the scope of what is claimed, without departing from the spirit of the invention.

In the accompanying drawings the preferred form of the invention has been shown.

30 In said drawings,

Figure 1 is a side elevation of a locomotive equipped with the signal constituting the present invention.

Figure 2 is a plan view of portions of the 35 track having tripping elements adjacent thereto for actuating the signal mechanism.

Figure 3 is a view partly in side elevation and partly in section of the signal mechanism.

Figure 4 is a section on line 4—4, Figure 3.

40 Referring to the figures by characters of reference A designates a locomotive provided with the usual steam whistle B the valve of which has a stem C on which is secured a piston D. This piston is mounted to work with-

45 in a small cylinder E and a spring F which bears against the piston serves to hold the valve of the whistle normally closed. A pressure supply pipe 1 opens into one end of the cylinder E and has a branch pipe 2 with branches which open at 2' into a series of cylinders 3 mounted on a casing 4. The number

50 of these cylinders is equal to the number of different signals to be sounded automatically by the whistle. A piston 5 is mounted in each cylinder and has a stem 6 projecting into a space 7 surrounded by the casing 4. A shaft

8 is journaled in the casing and extends through this space and is secured, at one end, to a worm gear 9 adapted to receive motion from a worm 10 secured to the shaft 11 of a 60 motor 12. A ratchet wheel 13 is mounted for rotation with the shaft 8 and a disk 14 is loosely mounted on the shaft, this disk being arranged against one side of the ratchet wheel or very close to it. A pawl 15 is pivotally 65 mounted on the disk as shown at 16 and has a head 17 at one end adapted to engage any one of the teeth of the adjacent ratchet wheel 13. A spring 18 attached to the disk and bearing against the pawl serves to thrust the pawl toward the ratchet wheel. Normally, however, the head 17 of the pawl is held out of engagement with the ratchet wheel by the piston rod 6 extending from one of the cylinders, there being a projecting nose 19 on one end of the 70 pawl which, when in engagement with the piston rod 6 serves to hold the pawl against movement into engagement with the ratchet wheel.

One of the disks 14 with a ratchet wheel 80 and pawl is provided for each signal to be sounded, there being a pin 20 slidably mounted in the casing above each disk so as normally to bear upon the periphery of the disk. Each disk has peripheral projections 21 so disposed relative to each other and so proportioned that, when the disk is rotated in one direction, these projections will successively shift and release the pin 20 bearing upon the disk, the time intervals between movements 75 of the pin being dependent upon the relative positions of the projections and their sizes.

All of the pins 20 are disposed where they can engage one arm of a lever 22 fulcrumed on the casing 4, the other arm of this lever being attached to the stem 23 of a valve 24. This valve is arranged within the pipe 1 and is normally in engagement with its seat so as to cut off communication between the whistle B and the source of pressure. It will be obvious that 90 when any one of the pins 20 is shifted out of normal position by its rotating disk 14 the valve 24 will be moved to open position so as to admit fluid under pressure to the cylinder E, thereby causing the whistle valve to open and allow fluid under pressure to flow to the whistle by way of a pipe 25.

A vent pipe 26 is provided for each of the openings 2' in the cylinders 3 and located at the lower end of each of these vent pipes is 110 a valve 27 connected to a lever 28. Valves 27 with levers 28 are arranged side by side so

as to be disposed at different distances from the sides of the locomotive. All of the valves 27 are normally closed. The track along which the locomotive is adapted to travel has 5 been indicated at G and wherever it is desired to sound a signal whistle a tripping block 29 is secured close to one of the rails. Some of the blocks are nearer the rails than others, the distance being dependent upon the par- 10 ticular lever 28 to be tripped when the locomotive arrives at the point where the tripping block is located. As before explained the disks 14 are provided with peripheral projections 21 which are arranged differently 15 on the several disks. Thus when one disk is rotated the pin 20 will be shifted to actuate lever 22 and open and close valve 24 to pro- 20 duce two long blasts of the whistle and two short blasts. A disk for this purpose has 25 been illustrated in Figure 3. Another disk might be designed for producing one long blast. In the structure illustrated the shaft 11 is driven continuously and shaft 8 with the ratchet wheels thereon is also rotated con- 30 tinuously. When one of the levers 28 comes against a tripping block 30 in the path thereof it opens the valve 27 so as to release pressure 35 from the cylinder 3 with which the actuated lever 28 is associated. As soon as pressure is released from this cylinder the piston 5, which normally holds a spring 31 under comp- 40 ression, will be released from the position shown in Figure 3, thereby withdrawing the rod 6 from engagement with the nose 19. Simultaneously with this action spring 18 45 will throw the pawl 15 into engagement with the adjacent ratchet wheel 13, thereby cou- 50 pling the selected disk 14 to the rotating shaft 8. Thus as this shaft rotates the projection 55 21 will successively shift the pin 20 and re- 55 lease it, thereby successively actuating lever 22 and valve 24 and successively operating the valve of the whistle B so that the desired signal will be sounded. Before the disk 14 completes one rotation the lever 28 will have 60 passed out of engagement with the tripping block 30 and the valve 27 will have been closed. Consequently pressure will be re- 65 stored in the cylinder 3 and piston 5 returns to its normal position with spring 31 under compression and stem 6 projected into the 70 space 7. Thus as the disk 14 completes one rotation the nose 19 will come against the end portion of the piston rod 6 which, acting 75 as a trip, will swing the head 17 of the pawl 80 out of engagement with the ratchet wheel 13. This will uncouple disk 14 from shaft 8 and said shaft can continue to rotate without pro- 85 ducing any further signal blast by the whis- 90 tle. Although the structure illustrated dis- 95 closes a motor for driving the shaft 8 continu- 100 ously, it is to be understood that, if desired, operating mechanism such as shown in my 105 patent before mentioned can be provided for 110 rotating this shaft.

In order that the whistle may be sounded at any time desired and independently of the automatic mechanism, suitable means located in the cab can be employed for depressing valve 24. This means can be in the form of 70 a spring supported foot lever or hand lever 32 having a plunger 33 extending downwardly therefrom and bearing on lever 22. Obviously when lever 32 is depressed either by using the foot or by pulling thereupon 75 with the hand, according to the location of the lever, the lever 22 will be moved downwardly and valve 24 unseated. Thus it will be seen that any desired signal can be given at 80 any time desired.

What is claimed is:

1. The combination with a signal device and a pressure controlling valve therefor, of pressure operated means for opening said valve, a cut off valve for controlling the flow 85 of pressure to said means, a plurality of disks mounted for independent rotation, separate means actuated thereby for operating the cut off valve, and trip controlled means for imparting a limited rotation to a 90 predetermined disk.

2. The combination with a signal device having a pressure controlling valve, of pres- 95 sure operating means for opening the valve, a check valve for controlling the flow of pressure to said means, a plurality of disks mounted for independent rotation, separate means actuating thereby for shifting the check valve, disk actuating mechanism, and separate trip controlled means for coupling 100 said mechanism to the respective disks.

3. The combination with a signal device having a pressure controlling valve and pres- 105 sure operated means for actuating said valve, of a cut off valve for controlling the flow of pressure to said means, a shaft, means for ro- 110 tating the shaft, a disk loosely mounted on the shaft, means for actuation by the disk for shifting the cut off valve from normal position, means for coupling the disk to the shaft, pressure operated means for holding 115 said coupling means in inactive position to permit rotation of the shaft independently of the disk, and trip controlled means for releasing said pressure controlled means to couple the shaft to the disk.

4. The combination with a signal device having a pressure controlling valve, and pressure operated means for opening the valve, of a cut off valve for normally holding 120 pressure from said means, a shaft, means for rotating the shaft, a disk loosely mounted on the shaft, means for actuation by the disk for shifting the cut off valve from normal position, means for coupling the disk to the 125 shaft, pressure controlled means for holding the coupling means normally inactive, and trip controlled means for momentarily re- 130 leasing pressure from said pressure operated means, thereby to momentarily release the 130

coupling means to active position to operatively connect the disk and shaft.

5. The combination with a signal device having a pressure controlling valve, and pressure operated means for opening the valve, of a cut off valve for holding pressure from said means, a shaft, means for continuously rotating the shaft, a plurality of disks supported by but loose upon the shaft, separate means operated by the respective disks when rotated for unseating the cut off valve, means combined with each disk and the shaft

for coupling said disk to the shaft, pressure operated means for holding the disks normally uncoupled from the shaft, separate 15 trip controlled means for releasing pressure from the respective pressure operated means, thereby to release a predetermined coupling means to operatively connect each disk to the shaft during a limited rotation of the shaft. 20

In testimony that I claim the foregoing as my own, I have hereto affixed my signature.

JAMES A. TAYLOR.
